AX

John M. Williams, Harlem, Mont.

Application August 14, 1936, Serial No. 96,095

3 Claims. (Cl. 145—3)

This invention relates to a novel and improved ax for general utility and has more specific reference to the construction of the head of the ax, wherein said head is provided with a detachable renewable or interchangeable cutting blade.

In reducing to practice the principles of the present inventive conception, I have evolved and produced a construction employing a standardized slotted head designed to accommodate detachable interchangeable cutting blades.

Briefly, the preferred embodiment of the invention comprises a dove-tail joint between the head proper and the detachable blade, wherein novel clamping means is utilized to securely fasten the parts together in reliable operating positions.

It is my primary aim to generally improve upon ax constructions by providing a structure characterized by simplicity, efficiency, durability, and economy.

Other features and advantages will become more readily apparent from the following description and drawings.

In the drawings, wherein like numerals are employed to designate like parts throughout the same:

Figure 1 is an end elevation of an ax constructed in accordance with the principles of the present invention.

Figure 2 is a side elevational view of the same.

Figure 3 is a detail section taken approximately on the plane of the line 3—3 of Figure 2.

Figure 4 is a fragmentary perspective view of one end portion of the especially constructed renewable or detachable cutting blade, or bit, as it is sometimes called.

Figure 5 is a section which may be said to be taken centrally on the plane of the line 5—5 of Figure 1.

Figure 6 is a detail perspective view of one of the parts.

Figure 7 is a fragmentary elevational end view of Figure 1 with the clamping or retaining means omitted for clearness of illustration.

The handle of the ax is denoted by the numeral 8 and the stationary part of the head is indicated as a unit by the numeral 9. The hammer end 9a of said head is of any suitable construction. The opposite end is fashioned to accommodate the novel renewable bit or blade 10. In accomplishing this result, it may be said that the casting is bifurcated and the furcations 11 are tapered into converging parallelism to form a keyway or accommodation channel therebetween. The lower longitudinal edges of the fea-

tures 11 are beveled as indicated at 12. At opposite ends the furcations, which are in effect jaws, are provided with special adapter notches 13, and the notches are shaped to accommodate and receive the correspondingly shaped clamping members 14 and 15. The member 14 constitutes the integral head of a bolt 16 and the remaining member 15 is in effect a washer with which the retaining nut 17 on the threaded end 18 of the bolt cooperates. Each clamping member is of block-like form and fits flush into the keeper notch and each member is also provided with substantially triangular extensions 19 fitting into correspondingly shaped notches or counter-notches formed in the main keeper notches. The bolt when in place, extends through the keyway or passage 20 shown to better advantage in Figure 7.

The body of the bit is of appropriate proportions and shape. The tenon-like key is indicated by the numeral 21 and fits into the keyway, that is, the space formed between the furcations 11. As shown in Figure 4, it is dovetailed in cross-sectional form so as to correspond to the space in which it is fitted. The upper end thereof is notched as at 22 to define retention extensions 23 cooperating with the adjacent correspondingly shaped pointed projections 19 on the respective clamping blocks 14 and 15. The portions 24 are undercut to define channels for the beveled features 11.

Novelty is believed to reside in the provision of an ax head having a horizontal or longitudinally elongated channel formed therein which is in effect a keyway for reception of the tenon-like retention rib or key 21, having associated therewith the clamping bolt and blocks or cleats 14 and 15.

Stated otherwise, these cooperating features may be broadly described as a head and bit having a coacting dovetailed joint connection. It is to be noted that the dovetailed tenon 21 is of a vertical height less than the corresponding dimension of the jaw-like furcations 11 so as to define between itself and the bottom of the channel a passageway 20 to accommodate the insertable and removable clamping bolt and retaining members or cleats 14 and 15 cooperable therewith. The interfitting features 19 and 23 are calculated to provide the desired security of maintenance between the parts when they are operatively clamped together. The provision of the block-like retaining members 14 and 15 receding or telescoping into the adapter notches which serve to accommodate them provides the desired flush arrangement on the outside edge of the structure.

to avoid the presence of projections such as would interfere with the chopping or cutting action.

It is thought that the description taken in connection with the drawings will enable a clear understanding of the invention to be had. Therefore, a more lengthy description is thought unnecessary.

While the preferred embodiment of the invention has been shown and described, it is to be understood that minor changes coming within the field of invention claimed may be resorted to if desired.

I claim:

- 15 1. In a structure of the class described, a head including a single body bifurcated at one end, the furcations being disposed in spaced converging relation and defining an open-ended keyway of dovetail cross-sectional form, a renewable cutting blade having a dovetail rib forming a key fitting removably in said keyway, the end portions of said key and keyway being notched and said notches defining keeper recesses, the width of said rib being less than the depth of the keyway to space the inner edge of said rib from the bottom of the keyway to define a bolt passage, an assembling and retaining bolt located in and extending through said passage, and complementary block-like retaining members carried by the end portions of the bolt, said retaining members being provided on opposed faces with extensions

constituting keeper elements engageable with said keeper recesses.

2. In a structure of the class described, an ax head bifurcated at one end to form an open-ended channel constituting a keyway, a renewable bit fashioned at one end with a rib constituting a key, and said key being removably fitted in said keyway, the depth of said channel being such as to space the bottom of the channel from the adjacent parallel inner surface of said rib 10 to define a bolt accommodation space, a bolt located in said space between the bottom of the channel and the adjacent surface of said rib, and retaining cleats on opposite ends of said bolt releasably engageable with the adjacent ends of 15 the key and keyway respectively.

3. As a new article of manufacture and as a component part of a structure of the class described, an ax head comprising a body bifurcated at one end, the furcations being disposed in spaced converging relation and defining an open-ended keyway of dove-tail cross-sectional form, the free longitudinal ends of said furcations being beveled, and said furcations at opposite ends of said keyway being provided with cleat receiving and accommodating notches, the inner ends of the respective notches being counter-notched 25 in the manner and for the purposes described.

JOHN M. WILLIAMS. 30
